UNITED STATES PATENT OFFICE.

JESSE W. COLE, OF TIPTON, MISSOURI.

HORSESHOE.

No. 808,436.

Specification of Letters Patent.

Patented Dec. 26, 1905.

Application filed April 14, 1905. Serial No. 255,594.

To all whom it may concern:

Be it known that I, JESSE W. COLE, a citizen of the United States, and a resident of the town of Tipton, Missouri, have invented certain new and useful Improvements in Horseshoes, of which the following is a specification containing a full, clear, and exact description, reference being had to the accompanying drawings, forming a part hereof.

My invention relates to improvements in horseshoes; and it consists of the novel features herein shown, described, and claimed.

Referring to the drawings, Figure 1 illustrates my improved horseshoe applied to a horse's foot. Fig. 2 is a top plan view of the horseshoe. Fig. 3 is a section taken on line 3 3 of Fig. 2. Fig. 4 is a section taken on line 4 4 of Fig. 2.

The object of my invention is to construct a horseshoe so as to give a springy or elastic movement to the horse's tread and is especially designed for trotting, pacing, and running horses.

Referring to the drawings in detail, 1 indicates the main body of the horseshoe, which is constructed in the usual manner.

2 2 indicates the heel portions in the form of rectangular blocks that are pivotally held by pins or bolts 3 to the rear ends of the shoe 1. The top surfaces of these heel portions 2 incline downwardly toward their rear ends, so that the upper surfaces of said rear ends are in a plane below that occupied by the top surfaces of the shoe 1. This construction provides for an elongated wedge-shaped space between said heel portions 2 and the under side of the rear part of the horse's hoof, as clearly seen in Fig. 1.

Secured to the heel portions 2 2 is a cross-bar 4, the end thereof being let into the heel portions, as illustrated in Figs. 3 and 4, and being secured to the heel portions 2 by means of countersunk screws 5.

6 indicates a metallic steel spring-plate, one end of which is secured on top of the bar 4 by means of a screw or rivet 7. The other end is secured beneath the toe portion of the horseshoe by means of screws or rivets 8.

9 indicates the usual holes in the shoe for nails, by means of which the shoe may be secured to the horse's hoof.

The heel portions 2 2 are pivoted so as to move in only one direction—that is, upwardly—when the shoe is applied to the hoof of the horse.

The spring-plate 6 produces the springy movement when the shoe is in use.

When a horse is shod with shoes of my improved construction and is traveling, the heel-pieces 2 are the first parts of the shoe to contact with the ground, and owing to said heel-pieces being yieldingly held to the shoe proper they will give or spring upward until they bear against the under side of the horse's hoofs, and then as said horse moves forward and hoofs are lifted said hoofs are given a slight impetus, owing to the resiliency of the springs 6. This has the effect of quickening the motion of the horse's feet as they leave the ground, which is the primary object of my invention.

Having fully described my invention, what I claim is—

1. A horseshoe, comprising a body portion; pivoted heel portions, a bar secured to the pivoted heel portions; and a spring-plate secured to the shoe proper and bar; substantially as specified.

2. A horseshoe, comprising a body portion; pivoted heel portions; a bar secured to said pivoted heel portions; and a spring-plate, one end of which is secured on the bottom portion of the bar and the other end secured to the top portion of the shoe proper; substantially as specified.

3. A horseshoe, comprising a body portion; pivoted heel portions; and a spring-plate; one end of which is carried by said heel portions and the other end secured to the toe portion of the shoe; substantially as specified.

4. A horseshoe, comprising a body portion; tapered pivoted heel portions; and a spring-plate, one end of which is carried by said heel portions and the other end secured to the toe portion of the shoe; substantially as specified.

In testimony whereof I have signed my name to this specification in presence of two subscribing witnesses.

JESSE W. COLE.
